UNITED STATES PATENT OFFICE.

BERNARD COLLINS, OF KENNERDELL, PENNSYLVANIA.

AUTOMATIC HIGH AND LOW WATER INDICATOR FOR STEAM-BOILERS.

SPECIFICATION forming part of Letters Patent No. 271,794, dated February 6, 1883.

Application filed August 1, 1882. (No model.)

To all whom it may concern:

Be it known that I, BERNARD COLLINS, of Kennerdell, in the county of Venango and State of Pennsylvania, have invented certain new and useful Improvements in Automatic High and Low Water Indicators for Steam-Boilers; and I do hereby declare the following to be a full, clear, and exact description of the invention, such as will enable others skilled in the art to which it pertains to make and use the same.

My invention relates to automatic high and low water indicators for steam-boilers, the object being to provide an indicator for boilers which will be simple and economical in construction and reliable in its operation, both as a high and low water indicator.

In the accompanying drawings, Figure 1 is an end elevation of a boiler provided with one form of my attachment; and Fig. 2 is a similar view of a boiler provided with a modified form of attachment.

A represents the boiler, having the steam-dome B.

C represents the upper, and D the lower, gage-pipe, each of which is provided with a discharge-cock, e, at its upper end.

E represents a vertical steam-valve, mounted upon an elbow pipe, E', projecting from the steam-dome; and from the side of the valve-easing e projects a pipe, F, suitably connected to a steam-whistle, G. A short standard, F', projects above the pipe F, and is slotted longitudinally to receive a horizontal lever, H, which is pivoted to the standard by a pivot, h. The lever H is provided at about its center with a downwardly-projecting lug, h², adapted to rest in a slot, h³, in the head of the valve E. Both ends of the lever are perforated to receive wires I I', the former being connected by means of an angular bracket or link, i, and adjusting nuts i², with the upper or high-water pipe, C, of the boiler, while the wire I' is connected by a similar bracket or link, j, and adjusting-nuts j² with the upper end of the low-water pipe D. These brackets or links i and j are of the peculiar construction shown, having their main portions x vertical and their ends x' bent horizontally in opposite directions. The upper ends of the links are then secured to the wires by the nuts i² j², while their lower ends are secured to the pipes C and D, as shown.

The operation of the above-described device is as follows: The pipe C is normally filled with steam and the pipe D with water. If the water in the boiler lowers to a point below the pipe D, the latter will at once be filled by steam, which will cause a lengthwise expansion of the pipe, thus forcing upward the end of the lever H adjacent to the steam-whistle. This will cause the opening of the valve E, when steam will be admitted to the whistle, thus sounding the alarm. The reverse of this operation is effected when the water rises above its proper level in the boiler. In the latter instance the pipe C receives water, which will cause a contraction of the pipe and a consequent depression of the adjacent end of the lever H, which opens the valve and admits steam to the whistle.

In the modification shown in Fig. 2, I dispense with the pipe F, with its standard F', and combine the steam valve and whistle. The latter is screwed into the elbow-pipe E' and has a vertical passage, through which the valve E passes.

The lever H is arranged relative to the pipes C and D in the same manner as above described, but the connecting-wires, instead of being connected rigidly to the lever and adjustably to the links i j, are rigidly pivoted to said links, and are connected to the lever by means of perforated blocks J, which receive the ends of the wires, the latter being held and adjusted by nuts i² j². These blocks are adapted to be adjusted horizontally on the lever H, to adapt them to boilers of different sizes. The lever H is supported by a bracket, K, secured to the stem g' of the whistle, said lever being pivoted to one side of the bracket by a pivot, g².

By the construction above described I obtain an indicator which is effective and reliable in its operation, and which prevents equally any overflow or damage by low water in the boiler.

It will be apparent that many slight changes in the form or construction of the different parts of my improvement may be resorted to without departing from the spirit of my invention, and hence I would have it understood that I do not limit myself to the precise construction shown and described, but reserve to myself the right to make such changes in construction as properly fall within the scope of my invention.

I am aware that the motion derived from the expansion and contraction of pipes, due to the introduction of steam or water into them, has been utilized to actuate a steam-whistle and sound an alarm, and I do not broadly claim devices for effecting such a result.

Having fully described my invention, what I claim as new, and desire to secure by Letters Patent, is—

- 10 1. The combination, with a steam-boiler, of a high-water contracting-pipe, a low-water expanding-pipe, a steam valve and whistle, and a lever connected by adjustable wires and links to the said pipes, substantially as set forth.
- 15 2. An indicator for steam-boilers, consisting

of the combination, with the high and low water pipes, of a steam-valve, a steam-whistle, and a lever, the latter being pivoted above said valve and adapted to rest therein, and provided at each end with adjustable wires and angular links, whereby it is connected respectively with the said pipes, substantially as set forth.

In testimony whereof I have signed this 25 specification in the presence of two subscribing witnesses.

BERNARD COLLINS.
